UNITED STATES PATENT OFFICE.

ARTHUR P. CONANT, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE DIAL.

Application filed June 26, 1923. Serial No. 6,585. Term of patent 14 years.

To all whom it may concern:

Be it known that I, ARTHUR P. CONANT, a citizen of the United States, residing at Fort Thomas, in the county of Campbell and State of Kentucky, have invented a new, original, and ornamental Design for Watchcase Dials, of which the following is a specification, reference being had to the

accompanying drawing, forming part thereof.

The figure is a face or front view of a watchcase dial showing my new design.

I claim:

The ornamental design for a watchcase dial, substantially as shown.

ARTHUR P. CONANT.
